(57) **CLAIM**

I claim the ornamental design for a gate insert, as shown and as described.

DESCRIPTION

FIG. 1 is a perspective view of the gate insert with gate and another gate insert.

FIG. 2 is the front view of the gate insert with gate.

FIG. 3 is a perspective view of the gate insert.

FIG. 4 is the front view of the gate insert

FIG. 5 is a back view of the gate insert.

FIG. 6 is a side view of the gate insert.

FIG. 7 is the other side view of the gate insert.

FIG. 8 is a top view of the gate insert; and,

FIG. 9 is bottom view of the gate insert.

The gate, wood inserts, handle, and additional gate insert are shown in broken lines in FIGS. 1 and 2 are for illustrative purposes only to show the environment and do not form part of the claimed design.
